CASTING APPARATUS

Robert G. Wilson, Long Beach, Calif.

Application December 20, 1943, Serial No. 514,884

2 Claims. (Cl. 22—122)

This invention relates to apparatus for casting diamond core bits and has for its object the provision of an improved apparatus of this character. The invention aims to provide an improved apparatus of the type in which the diamonds are held in position in a mold by means of a vacuum and in which the metal to form the diamond core bit is poured over the diamonds.

The apparatus of the invention comprises a cup-shaped base plate arranged to be mounted on a table or the like, a carbon, preferably graphite, mold supported in spaced position above the base plate and an annular electrical heating member surrounding the mold. In an advantageous embodiment of the invention, the electrical heating member is supported upon the base plate and has a circular central opening in which the mold is supported, the base plate, heating member and mold forming a closed space which is subjected to intermittent vacuum. The mold is preferably of the usual type and comprises an annular channel with a rounded bottom for receiving the metal to form the bit, and a multiplicity of small holes connecting the channel with the closed space in which the diamonds are held by the vacuum during casting. The mold is in direct thermal contact with the heating element and is heated to any desired temperature before the metal is poured into the mold.

In order to provide a body of metal above the bit to increase the pressure of the metal in the mold and control the cooling of the bit, a metal collar is mounted over the mold to form the outside wall of a mold extension. The upper surface of the mold is cut out or otherwise formed to leave an annular shoulder for centering a metal collar. One of the important features of the invention is a core of metal, for example steel, which is supported over the center of the mold and in the center of the collar. The mold has a central hole and the core a depending part which engages the hole to center the core. The core is a little smaller in outside diameter than the inner diameter of the bit, and the collar is sufficiently larger in inside diameter than the core that an appreciable body of metal extends upward from the bit between the collar and core.

The upper part of the core is tapered, for example conical or hemispherical, to facilitate its removal from the body of metal above the bit. The smaller diameter of the core than the inside diameter of the bit facilitates removal of the core through the inside of the bit. For the purpose of pulling the core out of the body of metal,

I provide any suitable engaging means, such as two or more inclined holes, in which gripping means, such as tongs or other extracting tool, may be inserted.

These and other novel features of the invention will be better understood after considering the following discussion taken in conjunction with the accompanying drawing, in which:

Fig. 1 is a side elevational view, with parts in section, of apparatus embodying the invention, and

Fig. 2 is a view along line 2—2 of Fig. 1.

The apparatus illustrated in the drawing comprises a table 1 on which is mounted a cup-shaped base plate 2 formed of iron or steel which is connected by pipe 3 to a vacuum pump not shown. The vacuum applied to the space 4 above the cup-shaped base plate is controlled by means of the quick action valve 5 and the relief valve 6. Any suitable type of vacuum gage 7 may be used to indicate the amount of vacuum and a filter 8 may be connected to the pipe to remove particles of metal from the vacuum system.

25 The base plate is preferably cylindrical in shape with an annular centering groove 10 in which the annular electrical heating element 11 is supported. The graphite mold 12 has a depending cylindrical portion which fits snugly inside a cylindrical opening of the heating element and is supported by the projecting shoulder 13. The mold has an annular channel 14 with cylindrical sides and a rounded bottom for receiving the metal to form the bit, and a central cylindrical centering hole 15 for receiving a cylindrical extension 16 of the hemi-spherical metallic core 17. The core 17 may be tapered inwardly in any suitable manner and may be conical, pyramidal, or the like, to facilitate its removal from the cast metal. The surfaces of connection between the cup-shaped base plate, the electrical heating element, the graphite mold and the metal core are sufficiently close that the elements are held in such contact that any suitable vacuum of from, say, 2 inches to 12 inches of water may be created in the space 4.

In order to provide a body of metal extending an appreciable distance above the actual core bit to apply pressure to the metal in the mold and to prevent undue cooling of the metal, the metal collar 20, preferably of iron or steel, is placed in supporting position on an upper edge of the mold and is centered by the projecting shoulder 13. The inner diameter of the collar is somewhat less than the outer diameter of the bit but a little

larger than the inside diameter of the core. The core is preferably, at its point of maximum diameter, slightly smaller than the inside diameter of the bit and has engaging means such as the inclined holes 21 into which gripping means, such as tongs or the like, may be inserted to pull the core out of the bit and body of metal.

The annular channel 14 in the mold has a number of closely spaced grooves 24 and ribs 25 extending in the longitudinal direction of the bit, and a multiplicity of small holes 26 radiating from the sides and the rounded bottom portion of the annular channel wherein the diamonds 27 are secured in position during casting by the vacuum in the space 4. The ribs 25 form channels 10 in the bit to enable water to be forced there- 15 through during drilling.

In forming a diamond core bit in the apparatus of the invention, the various elements of apparatus are assembled in the manner shown in the drawing. The electricity is adjusted by means of a rheostat (not shown) to provide the required amount of heat to heat the mold 12 to a temperature of around 750° F. By means of the valves 5 and 6, the pressure in space 4 is reduced to any desired pressure, say, around 12 inches of water pressure, and the diamonds are placed in position, one in each of the small holes. The molten metal to form the bit, such as a cobalt, nickel, chromium steel alloy having a Brinell hardness of around 450, is poured into the space between the core 17 and the collar 20 when at a temperature of around 2600° F. The metal flows into the annular groove of the mold causing the diamonds to be partially embedded therein and fills the space between the core and the collar, as shown in Fig. 1. This body of metal above the bit increases the density of the bit and provides a sufficient reservoir of heat to prevent undue cooling of the metal in the bit. After the metal is solidified, the collar is removed, the graphite mold broken away from the bit, and the core is pulled out through the center by means of a pair of

5 prongs which engage the holes 21. By means of a carborundum saw or the like, the body of metal extending above the bit is cut off and the bit is ready to be brazed or otherwise attached to a bit shank.

I claim:

1. An improved apparatus for casting diamond core bits which comprises a base plate, a mold, means for supporting the mold on the base plate, an electrical heating element in heat exchange contact with the exterior of the mold, a metal collar centered in and resting upon an upper portion of the mold, and a metal core centered in and resting upon an upper portion of the mold, said core being sufficiently smaller in outside diameter than the inside diameter of the collar that space is left for an appreciable body of metal above the core bit formed in the mold, and means for removing the core from the body of metal.

2. An improved apparatus for casting diamond core bits which comprises a base plate, an annular electrical heating member supported on the base plate, a graphite mold supported on the electrical heating member, means for creating a vacuum in the space between the mold, heating element and base plate, an annular channel in the mold for receiving the metal to form the bit, a multiplicity of small holes in the mold in which diamonds are held in position by the vacuum while the metal is being cast in the annular channel, a metal core centered in and supported upon the mold, said core having a tapered upper portion to facilitate its removal and a maximum diameter where it engages the mold which is slightly smaller than the inside diameter of the bit, and a metal collar supported upon and centered by the mold which surrounds the core in spaced relation leaving a space for an appreciable body of metal extending upwardly from the bit and over the core, and means for removing the core from the body of metal through the inside of the core bit.

ROBERT G. WILSON.
